EYELASH COMB AND CURLER

Helen Payes, Leonard Payes, and Sadie Payes,
New York, N. Y.

Application May 28, 1935, Serial No. 23,930

6 Claims. (Cl. 132—11)

This invention relates to an improved eyelash comb and curler, an object of the invention being to provide a device of this character which is curved or shaped to conform to the general contour of the eye and which can be readily moved upwardly engaging the lashes of the upper eyelid and functioning not only to comb the lashes, but also to impart thereto an upward curve or curl.

10 A further object is to provide a device of this character which may also be utilized to apply mascara, petroleum jelly, or other composition or liquid into contact with the lashes while combing and curling the same.

15 A further object is to provide a device of this character which can be manufactured and sold at an extremely low price and which will most efficiently perform the functions for which it is intended.

20 With these and other objects in view the invention consists in certain novel features of construction and combinations and arrangements of parts, all of which will be more fully herein-after described and pointed out in the claims.

25 In the accompanying drawing—

Figure 1 is an elevation illustrating one embodiment of our invention;

Figure 2 is a view in longitudinal section through the center of the device shown in Figure 1;

30 Figure 3 is a view in section illustrating the device in operative engagement with the eyelashes;

Figure 4 is a perspective view illustrating a modification;

Figure 5 is a view in elevation illustrating another modification; and,

Figure 6 is an end view of the device shown in Figure 5.

40 Referring more particularly to Figures 1 and 2 of the drawing, A represents a combination comb and curler supported by a holder 1 having a handle 2 thereon. This holder 1 and handle 2 may be, as illustrated, formed from a single length of wire—the intermediate portion of the wire twisted together to form a handle and the ends or extremities of the wire laterally offset and providing a bifurcated or forked holder for the comb. These furcations constitute arms 3

45 which are parallel to each other and which have openings or slots 4 at their ends to receive integral tongues 5 on the ends of the comb. It is to be noted that the comb is normally of a length greater than the distance between the arms 3

50 so that in order to hold the comb in the arms

it is curved or bowed and the tongues 5 positioned in the openings 4 so that the tendency of the comb to straighten maintains the comb securely held between the arms. In other words, the comb in this particular form of our invention is preferably of celluloid or other light resilient material which can be readily bent or curved into the shape desired and will by reason of its own resiliency maintain itself in this shape. The curvature of the comb conforms as nearly 10 as possible to the curvature of the eye so that when the comb is moved upwardly into contact with the eyelashes indicated at 6 in Figure 3 it will comb the lashes upwardly and at the same time will cause the lashes to curl. In order to 15 effectually curl the lashes, the body or backing of the comb between the teeth 8 is beveled or inclined as shown at 7 so that a more or less sharp edge is presented to the lashes and to curl them 20 upwardly.

In the modification illustrated in Figure 4 of the drawing, the comb A is made of hard rubber or other more or less rigid material and is normally curved and is provided centrally with an integral offset handle 9.

25 In the modification illustrated in Figures 5 and 6 of the drawing, the comb A is also normally curved and is provided with teeth 8 in both edges with an integral handle 10 extending from one end of the body of the comb. With this form of 30 comb, one set of teeth may be used for combing and curling the lashes of the right eye and the other set for combing and curling the lashes of the left eye by simply reversing the position of 35 the handle and utilizing first one hand and then the other.

In all forms of the comb, the toothed edges of the combs are curved. The high point is at the center of the comb and tapers to both ends. The body or backing is beveled or inclined between the teeth as shown at 7 in Figure 3 and it is readily understandable that our improved comb may be utilized as an applicator of mascara, petroleum jelly, or any other composition or liquid 40 which may be desirable for application to the 45 lashes.

While we have illustrated and described what we believe to be a preferred embodiment of our invention, it is obvious that various changes 50 might be made in the general form and arrangement of parts without departing from our invention, and hence we do not limit ourselves to the precise details set forth but consider ourselves at liberty to make such changes and alterations as 55

fairly fall within the spirit and scope of the appended claims.

We claim:

1. A device of the character described including a handle embodying a pair of spaced arms laterally offset relative to the handle, and a resilient bendable comb and lugs at the ends of the comb adapted to be inserted in the openings of the arms to couple the comb to the handle and hold the comb in curved formation.
2. A device of the character described, including a handle embodying a pair of spaced arms laterally offset relative to the handle, and a resilient bendable comb supported by the arms and held thereby in curved formation.
3. A device of the character described comprising an eyelash comb and curler including a body having teeth thereon to comb and curl the lashes of the eye, said teeth being disposed in a row at one edge of said body along a curved line which conforms substantially to the curvature of the eye lid in a direction extending between the nose and temple whereby the comb teeth can be moved upwardly in contact with substantially all of the eyelashes of the eye lid to turn said lashes upwardly.
4. A device of the character described comprising an eyelash comb and curler including a body conforming substantially to the curvature of the eye lid in a direction extending between the nose and temple, said body having teeth at one edge thereof disposed in a row extending along a curved line conforming substantially to said curvature of the eye lid whereby said teeth can be moved upwardly in contact with the upper eye lid and substantially all of the eye-

lashes of said lid to turn said lashes upwardly, the edge portions of said body between said teeth being inclined upwardly toward the outer surface of said body.

5. A device of the character described comprising an eyelash comb and curler including a body having teeth thereon to comb and curl the lashes of the eye, said teeth being disposed in a row at one edge of said body along a curved line which conforms substantially to the curvature of the eye lid in a direction extending between the nose and temple, and which is substantially co-extensive in length with the eye lid in said direction, whereby the comb teeth can be moved upwardly in contact with substantially all of the eyelashes of the eye lid to turn said lashes upwardly.

6. A device of the character described comprising an eyelash comb and curler including a body conforming substantially to the curvature of the eye lid in a direction extending between the nose and temple, said body having teeth at one edge thereof disposed in a row extending along a curved line conforming substantially to said curvature of the eye lid and substantially co-extensive in length with the eye lid in said direction, whereby said teeth can be moved upwardly in contact with the upper eye lid and substantially all of the eyelashes of said lid to turn said lashes upwardly, the edge portions of said body between said teeth being inclined upwardly toward the outer surface of said body.
